(57) **CLAIM**

The ornamental design for a fluid container, as shown and described.

DESCRIPTION

FIG. 1 is a rear, right side, top perspective view of a fluid container according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front, right side, bottom perspective thereof;

FIG. 9 is a front, right side, top perspective view thereof showing a lid of the fluid container in an open position;

FIG. 10 is a front elevation view thereof showing the lid in the open position;

FIG. 11 is a rear elevation view thereof showing the lid in the open position;

FIG. 12 is a right side elevation view thereof showing the lid in the open position;

FIG. 13 is a left side elevation view thereof showing the lid in the open position;

FIG. 14 is a top plan view thereof showing the lid in the open position;

FIG. 15 is a bottom plan view thereof showing the lid in the open position; and,

FIG. 16 is a front, right side, bottom perspective thereof showing the lid in the open position.

The dash-dash broken lines in the drawings are for the purpose of illustrating portions of the fluid container that form no part of the claimed design.

1 Claim, 10 Drawing Sheets
